UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

COMPRESSOR OUTFIT

Application filed October 8, 1925. Serial No. 61,362.

This invention relates to compressor outfitts, and more particularly to the water cooling system for the compressor and the driving engine therefor.

The compressor outfit herein shown is of the portable type and comprises generally a V-type compressor having jacketed cylinders, an internal combustion engine also provided with jacketed cylinders, and a radiator, there being improved piping connections between the several elements. In a V-type compressor as herein disclosed it is desirable to maintain each block of cylinders at substantially the same temperature; and to accomplish this I feed water to and discharge the same from the cylinder blocks in parallelism, so-to-speak.

My improved arrangement of parts is also particularly applicable to a portable type of compressor for it permits a very compact and symmetrical arrangement of the pipes.

In the accompanying drawings I have shown for purposes of illustration one form which my invention may assume in practice.

In these drawings,—

Fig. 1 is a side elevation of the portable compressor partly broken away to show the details of construction.

Fig. 2 is a plan view thereof with the top for the compressor outfit removed.

In the illustrative embodiment of my invention I have shown a portable compressor outfit having a wheel supported frame 1 carrying a compressor provided with cylinder blocks 2 and 3 arranged in a V-shaped manner upon a crank case 4. Driving mechanism for the compressor comprises preferably an internal combustion engine 5 connected in any usual manner with the compressor crank shaft. A usual radiator 6 mounted upon the front end of the frame has communication with the jacketed cylinders of the engine as by a pipe 7; and water is circulated through the jackets which surround each of the compressor cylinders and engine cylinders as by a pump 8 which is driven in any usual manner by the engine. It will be understood that the engine herein described is of a standard commercial form, and that the cylinder jacket thereof has an outlet 9 usually extending for-

wardly to discharge water into the top of the radiator 6. This discharge 9 preferably has a flange which is bolted to the engine cylinder and to adapt the same to my improved cooling system I merely remove and turn the same through 180° thereby causing the member 9 to discharge rearwardly. A flexible hose 10 is secured to the discharge 9 and to a pipe T 11 which has communication with oppositely extending branch pipes 12 and 13, the latter in turn communicating as by pipes 14 and 15 one with each of the compressor cylinder blocks 2 and 3. Discharge pipes 16 and 17 lead from the top of the respective compressor cylinder blocks and are connected to a common return water pipe 18 as by T's 19 and 20 respectively. The pipe 18 communicates at one end with the top of the radiator 6, and at its other end is provided with a cap 21. In order to adjust and support the pipe 18, a suitable nut and screw connection 22 cooperates with an upstanding top supporting member 23 carried by the frame 1. A top 24 is supported upon the frame 23 and the radiator 6. The pipe 18 is disposed beneath and covered by the top 24.

In operation the pump 8 will be actuated to pump water from the bottom of the radiator up through the engine cylinder water jackets, through the hose 10, from which the water will branch equally into the two compressor cylinder blocks. Due to this branch connection the temperature of the cooling water in each block will be substantially the same; and accordingly the compressed air as discharged from the compressor will have a substantially uniform temperature. The water discharge from the compressor cylinder blocks will then merge in the pipe 18 and flow back to the radiator to be cooled.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a compressor of the V-type having cylinders provided with cooling water jackets, an internal combustion engine also having a cooling water jacket, means for supplying cooling water to the jacket for said engine, means for conducting cooling water therefrom to the jackets for said compressor cylinders including a member having communication with the jacket for said engine cylinder at a central point and providing a conduit extending therefrom substantially longitudinally of said engine, and branch pipes leading from said conduit and entering the jackets for said compressor cylinders, and means for receiving the discharged water from the jackets for said compressor cylinders.
2. In combination, a V-type compressor having cylinders provided with cooling fluid chambers, an internal combustion engine for driving the same and also provided with a cooling fluid chamber, a source of supply for the cooling fluid, and means for circulating the cooling fluid from said source to the cooling fluid chamber for said engine and therefrom in parallelism through said compressor cylinder chambers.
3. In combination, a V-type compressor having cylinders provided with cooling fluid chambers, an internal combustion engine for driving the same and also provided with a cooling fluid chamber, a heat exchange device, means for circulating cooling fluid from said device to the cooling fluid chamber for said engine and therefrom in parallelism through said compressor cylinder chambers, and means for conducting cooling fluid from said compressor chambers to said heat exchange device including a common pipe.
4. A portable compressor outfit comprising a frame, a compressor thereon provided with cooling water jacket means, means for circulating water in a closed circuit for cooling said compressor comprising means for withdrawing heat from the water, means for circulating water therefrom to said cooling jacket means and for returning the water thereto from said cooling jacket means including a pipe extending longitudinally of said compressor and having a portion between its ends disposed directly above said compressor and a supporting member for one end of said pipe extending upwardly from said frame, the other end of said pipe being supported by said heat withdrawing means.
5. A portable compressor outfit comprising a frame, a compressor cylinder thereon provided with cooling water jacket means, a radiator at one end of said frame, means for circulating water for said compressor cylinder jacket means from and to said radiator including a pipe extending longitudinally of

and above said portable compressor with an intermediate portion thereof directly overlying the compressor, and a supporting member for one end of said pipe extending upwardly from said frame, the other end of said pipe being supported by said radiator.

6. A portable compressor outfit comprising a frame, a compressor cylinder thereon provided with cooling water jacket means, a radiator at one end of said frame, means for circulating water in a closed circuit for cooling said compressor cylinder comprising means for conveying water from said radiator to said jacket means and means for conveying water from said jacket means to said radiator including a pipe extending longitudinally of said frame and above said compressor cylinder with an intermediate portion thereof directly overlying the compressor, and a supporting member for one end of said pipe extending upwardly from said frame, the other end of said pipe being supported by said radiator.

In testimony whereof I affix my signature.

FRED D. HOLDSWORTH.
